UNITED STATES PATENT OFFICE.

FRANKLIN F. BRADLEY, OF CHICAGO, ILLINOIS, ASSIGNOR TO BRADLEY & VROOMAN COMPANY, OF CHICAGO, ILLINOIS, A CORPORATION OF ILLINOIS.

SPRAYING APPARATUS.

1,220,942.

Specification of Letters Patent. Patented Mar. 27, 1917.

Application filed October 7, 1914. Serial No. 865,487.

To all whom it may concern:

Be it known that I, FRANKLIN F. BRADLEY, a citizen of the United States, residing at Chicago, in the county of Cook and State of Illinois, have invented a certain new and useful Improvement in Spraying Apparatus, of which the following is a full, clear, concise, and exact description, reference being had to the accompanying drawings, forming a part of this specification.

My invention relates to spraying devices and is of particular service in the formation of spraying devices that are adapted to the distribution of paint, varnish, etc.

The invention has for one of its objects the provision of a spraying device that is adapted to the production of a spray of atomized liquid that is much more evenly distributed throughout the spray than was hitherto possible with prior devices. In practising this feature of my invention I employ a plurality, say two, substantially parallel collocated spraying nozzles adapted to the production of two sprays which are preferably initially distinct but which, owing to the collocation of the nozzles, are intermingled to effect the desired distribution of the atomized liquid in that portion of the combined spray where application of the atomized liquid is to be effected.

The invention has for another of its objects the provision of an improved mechanical construction of spraying nozzles, and for another of its objects the provision of improved means taking part in effecting the discharge of the liquid.

I will explain my invention more fully by reference to the accompanying drawing showing preferred embodiments thereof and in which Figure 1 is a side view of a spraying device constructed in accordance with my invention, parts being shown in section, the association of the spraying device with the air pressure tank and a source of liquid supply being diagrammatically indicated; Fig. 2 is a sectional plan view on line 2 2 of Fig. 3; Fig. 3 is an illustration similar to a part of the illustration contained in Fig. 1 but on a larger scale; Fig. 4 is a sectional view on line 4 4 of Fig. 3; and Fig. 5 illustrates a modification.

Like parts are indicated by similar characters of reference throughout the different figures.

Referring first more particularly to the

construction shown in Fig. 1 and to the views which illustrate characteristics that are common to the structures of Figs. 1 and 5, I have illustrated an apparatus which includes a pressure tank 1 that may contain 60 air having a normal pressure of sixty pounds per square inch. The outlet tube 2 of this air tank is connected by a flexible hose 3 with a rigid tube 4 that is carried by a suitable handle 5. A tank 6 contains the paint, 65 varnish or other liquid (illustrated at 7) which the atomizer of my invention is to diffuse in the form of a spray. An air inlet tube 8 carried by the tank 6 serves to connect a flexible air hose 9 with a rigid tube 70 10 also carried by the handle 6. An outlet tube 11 is connected by flexible hose or pipe 12 with the rigid pipe 13 that is also carried by the handle 5. The air pipes 4 and 10 are adapted for communication at their upper 75 ends when the valve 14 is opened consequent upon depression of the thumb head 15 of the valve 14, at which time air is also supplied under pressure to the air pipe 16 which extends to the spray nozzle structure illustrated at 17, the liquid conveying pipe 13 also extending to this structure. A check valve 18 is located in the pipe 10 and permits the flow of air under pressure through pipe 10 to the tank 6 for the purpose of forcing liquid from this tank through the pipe 13 to the nozzle structure 17. When the apparatus is out of action, at which time the valve 14 is closed, back pressure of air through the pipe 10 will force the check 80 valve 18 shut so that there is no flow of air under pressure through the pipe 16 whereby a desired degree of air pressure may be maintained upon the liquid in the tank 6 to enable the immediate flow of liquid from 85 this tank when the valve 14 is reopened. I do not limit myself to the use of ordinary tubing for the air and liquid conveying ducts.

The nozzle structure which I prefer to employ with the apparatus above specifically described forms another part of my invention but equipment which I have specifically described for effecting the discharge of liquid that is to be sprayed is not to be limited in its association to the preferred form of nozzle structure. In accordance with this feature of my invention the nozzle head includes in its formation a block of metal 19 which as two substantially parallel bores 20 110

and 21 formed therein, arranged transversely of the nozzle head and extending to one end of the nozzle head, these bores being normally closed at the latter end of the nozzle head by separate screw caps or closures 20¹, 21¹ in threaded engagement with the nozzle head to enable them to be cleaned. The liquid pipe 13 communicates with the bore 20 and the air pipe 16 communicates with the bore 21 whereby liquid and air are respectively supplied to these bores. Two parallel collocated tubular liquid educting nozzles 22, terminating at the front end of the nozzle head, are passed diametrically or transversely through the bore 21 into communication with the bore 20 whereby liquid may be discharged from the bore 20 through the nozzles 22 which extend longitudinally of the nozzle head. Annular spaces 23 surround the nozzles 22 and intervene between the same and the nozzle head 19, these spaces being sufficiently limited to enable the air to issue from the bore 21 therethrough with sufficient force first to draw the liquid through the nozzles 22 and thereafter thoroughly atomize the same.

In the form of the invention illustrated in Fig. 5 the liquid tank 6 is replaced by the liquid tank or receptacle 24 which is mechanically coupled with the pipe 13 by means of the set screw 25, the pipe 10 and the check valve 18 being omitted in this arrangement. In the structure illustrated in Fig. 1 the liquid is not only withdrawn due to the air which is flowing under pressure through the annular spaces 23 but is also withdrawn due to the pressure upon the liquid in the tank 6 whereas in the structure of Fig. 7 there is no artificial pressure upon the liquid in the receptacle 24, total reliance being placed upon the air flowing through the spaces 23 to effect the flow of liquid in the nozzles 22. By means of the nozzle structure described and the parts correlated therewith outwardly flaring conical streams of atomized liquid are produced. As is well known by those skilled in the art the atomized liquid is denser at the axial portions

of the separated parts of the two conical streams so that if but one nozzle were used 50 alone the atomized liquid would not issue from the apparatus in a well distributed condition. By employing two nozzle structures the conical streams of atomized liquid merge a suitable distance therefrom, the 55 particles of the two streams intermingling and bombarding each other to effect a redistribution which is substantially even at any right section of the composite stream.

While I have herein shown and particularly described preferred embodiments of my invention I do not wish to be limited to the precise details of construction shown as changes may readily be made without departing from the spirit of my invention, but 65 having thus described my invention I claim as new and desire to secure by Letters Patent the following:—

An atomizer provided with a nozzle head having two substantially parallel bores arranged transversely of the nozzle head and each extending to one end thereof, one of these bores being for communication with a source of liquid to be sprayed and the other for communication with a source of 75 air under pressure; a separate screw cap for each of these bores at the end of the nozzle head to which such bore extends and in threaded engagement therewith; and a nozzle tube extending longitudinally of the 80 nozzle head and terminating at the front end of the nozzle head and extending through the latter bore into communication with the other bore, there being space at the exit end of the nozzle tube intervening 85 between this tube and the nozzle head, this space affording communication between the air conveying bore and the exterior of the nozzle head.

In witness whereof, I hereunto subscribe 90 my name this 30th day of September A. D., 1914.

FRANKLIN F. BRADLEY.
